[57] CLAIM

The ornamental design for a triangle ridge golf shoe spike, as shown and described.

DESCRIPTION

FIG. 1 is a perspective view of a triangle ridge golf shoe spike, showing my new design;
FIG. 2 is another perspective view thereof;
FIG. 3 is a bottom plan view thereof;
FIG. 4 is a side elevational view, the opposite side being a mirror image thereof; and,
FIG. 5 is a top plan view.
The broken line showing of a portion of a shoe in FIG. 1 is for illustrative purposes only, and forms no part of the claimed design.
